UNITED STATES PATENT OFFICE.

WARREN FRANKLIN CLARK, OF CLEVELAND, OHIO.

WATER-HEATING DEVICE.

Application filed July 14, 1921. Serial No. 484,801.

To all whom it may concern:

Be it known that I, WARREN F. CLARK, a citizen of the United States, residing at Cleveland, in the county of Cuyahoga and State of Ohio, have invented a certain new and useful Improvement in Water-Heating Devices, of which the following is a full, clear, and exact description, reference being had to the accompanying drawings.

This invention relates to water heating devices of the so-called instantaneous type wherein opening of a faucet automatically induces the operation of the heating device which acts upon the flowing stream to raise the water to the desired temperature, and closing of the faucet automatically stops the operation thereof. The present invention illustrates an instantaneous heater of the electric type wherein the current is turned on and off by changes in the pressure of the water without employing any electric connections to the faucets or valves by which the flow is controlled. The objects of the invention are the provision of an apparatus of this type of simple and rugged construction which shall be cheaply made, readily cleaned, reliable in operation, and economical of current while further objects and advantages of the invention will become apparent as the description proceeds.

In the drawings accompanying and forming a part of this application I have shown one embodiment of my invention, Fig. 1 being a longitudinal sectional view of the apparatus and Fig. 2 a detail view illustrating the direction of current flow.

Describing by reference characters the parts shown in these drawings, 1 and 2 represent metallic tubes having their walls formed with spaced helical corrugations 3-3 constituting seats for adjacent smooth walled tubes 4 and 5, respectively, which co-operate with the first named tubes to form narrow helical passages. The tube 2 is sufficiently smaller than the tube 4 to define an annular space 6 in which is located an electric heating device which thus acts upon both sets of channels at one time; means being provided so that the liquid having passed through the device in one direction through one set of channels is turned backwardly and flows in the opposite direction through the other set of channels.

In the present embodiment the outer pipe 1 is extended longitudinally beyond the other pipes and flanged at 10-10 into en-

gagement with rings 11 and 12. Near one end, hereinafter called the upper end though the position in space is immaterial, the tube 1 is formed with a lateral opening 13 for the attachment of the inlet pipe 14, and above this point the end of the tube 4 is flared outwardly as shown at 15 to engage the tube 1 and close the passageway. Detachably secured to the ring 11 is a terminal member 18 having a plug portion 19 depending inside the ends of the tubes 1 and 4 and also provided with a central nipple 20 receiving the end of the tube 2. The member 18 is provided with a central longitudinal bore 21 in which is threaded the outlet pipe 22, and also with a pair of apertures 23 communicating with the annular space 6 and carrying the electric terminals 24-24.

The heating device can be of any suitable material or construction. In the present embodiment I have shown a mica tube 25 wound upon the tube 2 and itself carrying the resistance wire 26 which is non-inductively wound so as to bring both its terminals at the upper end. At its lower end the annular space 6 is closed by a suitable member 27 which can be of either insulating material or conducting material and can be separate from or integral with any of the adjacent parts as may be desired, although I have shown it as made of metal and separate from the surrounding members. I have shown the pipes 4 and 5 as merely pressed longitudinally into their seats so as to cause most of the liquid to pass through the spiral passageways while enabling ready dismantling in case clogging occurs. Thus assuming that the tube 4 is fastened to the plug 19 (since it is undesirable to disrupt the electric heating element) if the top screws be removed the entire inner part can be lifted out of the tube 1; similarly if the bottom of the device be removed the tube 5 can be withdrawn, an eye 28 being preferably provided for this purpose. Passage through the tube 5 is prevented by a suitable closure 29 at some point therein.

This bottom preferably consists of a chambered member 30 clamped to the ring 12, a diaphragm 31 being interposed. Located between this member and diaphragm is the spring 32 and slidably mounted in this member and engaging the diaphragm is a plunger 33 whose outer end engages the removable lever 34 of an electric contact 35. A suitable spring 36 acting in the same di-

rection as the spring 32, tends to hold the contact members together, both springs opposing the pressure of the diaphragm 31 which tends to hold these contact members apart. When the faucet (not shown) connected to the pipe 22 is closed the outward pressure on the diaphragm holds the switch open and prevents the flow of current, but upon the opening of such faucet this pressure is at once released, the switch is closed and the current begins to flow. The body of the device is surrounded by a metal jacket 40, between which and the tube 1 is interposed the heat insulating material 41, a channeled 42 being left at one side for the electric wires 43 which connect the switch 35 with the terminals 24. The switch end is closed by a removable cap 44 and the terminal end by a removable cap 45, the wall of which is apertured for the attachment of the separable connector 46.

Owing to the very large heating area the operation of the device is very quick and owing to the fact that the heating element is entirely surrounded by water the waste of current is very small. Also there is practically no water heated that is not used, the liquid capacity being very small. The device can be cheaply made and easily repaired and cleansed but I do not limit myself to details of construction or arrangement except as the same are recited in my claims as many changes can be made.

Having thus described my invention what I claim is:

1. In a liquid heating device, in combination, a sheet metal tube having its wall corrugated in a helical manner to produce an integral rib, a cylindrical metal tube removably seated against such ribs and defining with the first tube a narrow helical passageway, and an electric heating unit closely fitting the wall of one of said tubes.

2. In a liquid heating device, in combination, a pair of metal tubes of unequal size each having a helically ribbed wall and arranged one inside the other, a cylindrical metal tube removably seated against the ribs of each of the first mentioned tubes so as to define a narrow helical passageway therewith, there being a narrow annular space between the inner and outer sets of tubes, an electrical heating element in such annular space, and means establishing communication between the inner and outer passageways at one end.

3. In a liquid heating device, in combination, an electrical heating element of cylindrical form, and cylindrical tubes being of sheet metal and having its wall corrugated in a helical manner to produce an integral rib defining a sinuous liquid channel, the tips of one set of ribs engaging the surface of said heating element whereby to define one side of such channel having a spiral

groove in its wall defining a sinuous liquid channel.

4. In a liquid heating device, in combination, an electrical heating element of cylindrical form, channeled members within and without said element, a connecting member at one end of said device whereby liquid is conveyed from one channel to the other, inlet and outlet pipes connected to the other ends of said channeled members, an electric switch in circuit with said heating element, and pressure responsive means carried by said connecting member and operative upon decrease in the liquid pressure to close said switch.

5. In a liquid heating device, in combination, a chambered member, a yielding diaphragm carried thereby, an electric heating element, a channeled member thermally connected to said heating element and adapted to convey liquid to one face of said diaphragm, there being an inlet to said channeled member at a distance from said diaphragm, an electric switch in circuit with said heating element, an operating member connecting said switch with said diaphragm, and spring means resisting the liquid pressure against said diaphragm.

6. In a liquid heating device, in combination, a terminal member, a pair of concentric tubes rigidly connected thereto at one end and connected together at the opposite end, an electric heating element located in the annular space between said tubes, and other tubes slidably mounted inside and outside said first tubes, one tube of each pair having a helical rib which snugly engages the surface of the mating tube to produce helical liquid passages inside and outside said heating element.

7. In a liquid heating device, in combination, a plurality of concentric cylindrical tubes, arranged one inside the other, certain of said tubes being connected together at their ends to form an annular chamber and other tubes both inside and outside the same being spaced from said tubes to form liquid passageways, an electrical heating element in said annular chamber, an electric switch in circuit with said heating element, and means operative by changes in the liquid pressure for operating said switch.

8. In a liquid heating device, in combination, a substantially cylindrical wrought metal tube having its wall corrugated in a helical manner to produce an integral rib, a second substantially cylindrical metal tube removably seated against such ribs and defining with the first tube a narrow helical liquid passageway, and means for heating the wall of at least one of said tubes.

In testimony whereof, I hereunto affix my signature.

WARREN FRANKLIN CLARK.
